CHARLES E. SMITH, OF LOWELL, MASSACHUSETTS, ASSIGNOR TO HIMSELF, JOHN S. JAQUES, AND FRANK T. JAQUES, OF THE SAME PLACE.

Letters Patent No. 83,331, dated October 20, 1868.

IMPROVEMENT IN SPINDLE FOR SHUTTLES.

The Schedule referred to in these Letters Patent and making part of the same.

To all whom it may concern:

Be it known that I, CHARLES E. SMITH, of Lowell, in the county of Middlesex, and State of Massachusetts, have invented certain new and useful Improvements in the Spindles of Loom-Shuttles, of which the following is a full, clear, and exact description, reference being had to the accompanying drawings, making part of this specification, in which—

Figure 1 represents the top side of one of my improved shuttle-spindles;

Figure 2, a side elevation, with a section of a cop of filling, B, as applied to the spindle for weaving;

Figure 3, a central longitudinal section on the line A B of fig. 2;

Figures 4 and 5 are modifications of my invention;

Figure 6 represents the top side of an ordinary shuttle-spindle; and

Figure 7 a horizontal plane section of fig. 6, with a cop shown in section.

This invention relates to that kind of shuttle-spindles which have long been known as split spindles, and which are employed where the filling used for weaving is spun on mules, and not on throste-frame, and on cops, and not on bobbins, and has for its object to retain the cop on the spindle, and prevent the same being upset or separated by the sudden blows of the shuttle which carries the spindle and the cop of filling.

The ordinary split spindles which are used in shuttles, and which carry cop-filling, are made in two parts, *a a*, and either welded or brazed together at their ends, and finished smoothly, and gradually tapered from the end to the shoulder *b*. The parts or sides *a a* are sprung apart about one-eighth of an inch, so that when the cop of filling is pushed on to such smooth-tapered spindle, the parts or sides are pressed together, thereby producing friction, for the purpose of holding the cop on the ordinary spindle.

This limited friction between the interior of the cop of filling, (which has a hole through it, formed by the mule-spindle on which it was spun,) and the exterior of the smooth-tapered spindle, is inadequate for the certain retention of the cop on the spindle, and by the sudden and violent blows of the shuttle against the pickers at the ends of the lay, the cop of filling is frequently upset or separated, when only a small portion of the filling has run off, which necessitates the removal

of the separated cop of filling, which is thrown out as waste.

To obviate the above-named difficulty, and prevent the frequent waste of valuable material, I take the same kind of spindle, and before springing the sides *a a* apart, and while the said spindle is being finished, and form therein several annular notches or serrations and shoulders, *c*, as shown in figs. 1, 2, and 3, by removing a portion of the substance of the spindle, and tapering the same from the highest part of one shoulder to the next beyond, as also clearly shown.

I then spread or spring the sides *a a* apart, and the spindle is ready to be applied to the shuttle, and to receive the cop of filling for the weaving-operation, which cop is pushed on to the spindle in the usual way, passing easily over the shoulders *c*, which prevent the cop being too easily removed.

When the cop of filling is thus applied to this improved spindle in a shuttle, and the shuttle put in operation in the loom, I have found it impossible to upset or separate or derange the filling to retard its proper action, and all the filling will run off, leaving the spindle bare, and the cop-tube *g* free for removal. The shoulders *c* hold the filling, and prevent the separation of the cop.

Instead of annular serrations and shoulders, I sometimes form simply transverse notches, *e*, in the sides *a a*, as shown in fig. 4, and I have found these notches to answer nearly or quite as well for holding the cop of filling as the annular shoulders *c*, which I consider equivalents of each other.

Instead of the shoulders *c*, or the notches *e*, I sometimes form annular corrugations or swells on the spindle, with intervening hollows between them, as shown in fig. 5.

These swells and hollows serve very well for holding the cop of filling on the spindle, but I prefer the shoulders or the notches, as before described.

What I claim as of my invention, and desire to secure by Letters Patent, is—

A split shuttle-spindle, notched or serrated on both sides, or on its entire circumference, substantially as and for the purposes set forth.

Witnesses: CHARLES E. SMITH.
